VELOCIPED

Kenneth W. Bader, Los Angeles, Calif.

Application April 25, 1950, Serial No. 9,462

Term of patent 14 years

(Cl. D34—15)

To all whom it may concern:

Be it known that I, Kenneth W. Bader, citizen of the United States, residing at Los Angeles, in the county of Los Angeles and State of California, have invented a new, original, and ornamental Design for a Velocipede, of which the following is a specification, reference being had to the accompanying drawing, forming part thereof.

The figure is a perspective view of a velocipede, showing my new design. The opposite side is similar to that shown.

The characteristic feature of the device resides in the full line portion of the drawing.

I claim:

The ornamental design for a velocipede, as shown and described.

KENNETH W. BADER.
